United States Patent Office.

ELIAS INGRAHAM, OF BRISTOL, CONNECTICUT.

Design No. 4,979, dated June 6, 1871.

DESIGN FOR CLOCK-CASE.

The Schedule referred to in these Letters Patent and making part of the same.

I, ELIAS INGRAHAM, of Bristol, in the county of Hartford and State of Connecticut, have invented or produced a new and original Design for a Clock-Case, of which the following is a specification.

My invention relates to the molding which forms the frame of a clock-case, and consists of alternate stripes of light and dark woods, extending across said molding, as hereafter described.

Figures 1, 3, 4, and 2 show, respectively, slanting, half-octagon, square, and round-topped clock-cases, each embodying my invention.

The body of the case is mounted on a suitable base, C, figs. 3 and 4, the two comprising the frame of the case, which frame consists mainly of the molding A, of any of the usual styles, and is composed of light and dark woods, 1 2.

For straight moldings I prefer to have the pieces or

stripes run obliquely across the molding A, as shown in all of the figures; but for round-top cases I arrange them as shown at the top in fig. 2.

B designates a flat panel inside of the frame, over which panel any desired style of sash may be placed.

The stripes 1 2 should be parallel in each molding; but the molding may be made in sections, as shown in figs. 3 and 4.

I claim as my invention—

The design for the molding A of a clock-case frame, consisting of alternate transverse stripes of light and dark woods 1 2, substantially as shown and described.

ELIAS INGRAHAM.
